US0D1038597S

(12) **United States Design Patent** (10) **Patent No.:** **US D1,038,597 S**
(45) **Date of Patent:** **** Aug. 13, 2024**

(54) **SHOE**

(71) Applicant: **Zhuo Xing Cheng Pin (Ningbo) Design Co., Ltd**, Zhejiang (CN)

(72) Inventor: **Jintao Wang**, Jiangsu (CN)

(**) Term: **15 Years**

(21) Appl. No.: **29/917,447**

(22) Filed: **Nov. 20, 2023**

(51) **LOC (14) Cl.** **02-04**

(52) **U.S. Cl.**

USPC **D2/946**; D2/947; D2/914

(58) **Field of Classification Search**

USPC D2/896, 897, 900, 902, 906–912, D2/913–924, 946–962, 969–978; D8/1; D15/10, 26, 28

(57) **CLAIM**

The ornamental design for a shoe, as shown and described.

DESCRIPTION

FIG. 1 is a right side, top perspective view of a shoe, showing my new design;

FIG. 2 is a left side, bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The dashed broken lines in the figures are for the purposes of illustrating portions of the shoe that form no part of the claimed design.

1 Claim, 8 Drawing Sheets
